ELECTROLYTIC WATER CORRECTION
DEVICE

Edgar M. Butler, New Orleans, La.

Application July 15, 1947, Serial No. 761,127

5 Claims. (Cl. 204—248)

1

This invention relates to an electrolytic water correction device, and more particularly to a device especially adapted for use in boilers and the like where the water level is too low with respect to the pipes to permit installation below the water level of other forms of devices.

Many former water correction devices have depended upon being bolted or otherwise attached to the boiler tubes or to the walls of boilers and the like. This method is not effective where the water level is normally just above the pipes of the boiler, since it is not possible conveniently to place so as to be wholly immersed.

In accordance with the principles of my invention, I provide an electrolyte water correction device comprising a core of metal having a coiled spring wrapped therearound, and a pair of centrally apertured triangular support members threaded onto said spring to any desired position thereon. The triangular supports are adapted to rest between adjacent pipes of the boiler or the like and operate effectively even though the water level is only slightly above the pipes. Since the core is well surrounded by the spring, there is little danger of large pieces of the core falling in the boiler.

The spring may be of metal of different electromotive potential with respect to the core to set up a galvanic action when the device is immersed in boiler water. If zinc is selected as the negative metal and copper, silver, phospho-bronze, or silver-plated foundation metal as the positive metal, the result is to liberate zinc ions into the water. The term "negative" is applied to metals above hydrogen in the electromotive force series and the term "positive" to those metals that are below hydrogen in the series.

The triangular support members are preferably made of a positive metal or alloy such as copper, or brass and may be provided with inwardly extending perpendicular fins. These fins likewise are preferably of positive metal and have a two-fold purpose. The first is to increase the surface area of positive metal which increase tends to promote the efficiency of the device by causing more rapid ionization. Secondly, the fins insure that no matter to what extent the core disintegrates, the support members will not fall through the pipes.

It is therefore an important object of the invention to provide an electrolytic water correction device particularly adapted for use in boilers having a low water level.

It is a further important object of this invention to provide an electrolytic water correction device particularly adapted for ready, safe mounting on pipes of boilers having a low water level therein.

It is a still further important object of this invention to provide an electrolytic water cor-

rection device of simple, inexpensive construction, permitting assembly and replacement of parts with great ease, and yet a device which is extremely efficient and insures against the possibility of any parts or large pieces falling from the pipes upon which it is mounted.

Other and further important objects of this invention will be apparent from the disclosures in the specification and on the accompanying drawings.

On the drawings:

Figure 1 is a fragmentary elevational view partly broken away of a low level fire tube boiler in which is inserted the electrolytic water correction device embodying the principles of my invention;

Figure 2 is an enlarged side elevational view of the electrolytic water correction device; and Figure 3 is a sectional view taken substantially on the line III—III of Fig. 2.

As shown on the drawings:

The reference numeral 10 indicates generally a boiler of the fire tube type having a low water level therein represented by the dotted line 11. It is to be noted that, referring to Fig. 1, the water level 11 is just above the tubes so that it would be difficult if not impossible to operatively mount a device having any considerable height. Within the boiler are a plurality of horizontally spaced rows of fire tubes designated by the reference numeral 12. Adjacent tubes of any two groups generally lie in the same horizontal plane.

The electrolytic water correction device 13 of my invention is particularly adapted to be mounted between adjacent top tubes of any two groups of pipes 12 desired, as shown in Fig. 1. As best seen in Figs. 2 and 3, the device comprises a core 14 of a negative metal of the electromotive force series surrounded by a helical coil 15 preferably formed of or surfaced with a positive metal of the electromotive force series. This coil 15 is illustrated as fitting tightly over the core and having opposite ends 16 and 17 adapted to be turned inwardly to extend transversely of the core ends and thus prevent the core from becoming disengaged.

Adapted to be threaded onto the spring at either end are a pair of triangular support members 18 and 19 illustrated as equilateral triangles. These members have central openings of a diameter somewhat greater than that of the core 14 but smaller than the outside diameter of the coil 15 and are provided with arcuate recesses 22 extending outwardly from such openings for receiving a portion of a turn of the coil therethrough as the members are threaded onto the coil. The turns of the coil are preferably so close together as to exert a restraining frictional pressure on the support members when threaded thereon, thus holding them in a proper orientation. The

support members are preferably of positive metal of the electromotive force series.

In order to enhance the electrolytic efficiency of the device, fins 24 of positive metal of the electromotive force series are preferably provided extending inwardly from the apices of the support members and at right angles to the planes of the support members. Said fins 24, like the support members 18 and 19, are formed of relatively thin plate stock and the fins are secured to the inner surfaces of said members, as by brazing, to be, in effect, integral therewith. In addition to increasing the positive metal surface area, these fins further serve to insure that the device will not fall between the pipe rows even though the core is completely disintegrated and the coil is quite flexible. This results from the fact that if the support members turn so that they could slip between the pipes, the fins will then extend transversely of the pipes and be supported thereby. Furthermore, the fins are so disposed about the spring sheath 15 as to inhibit bending or sagging thereof.

It will be evident from the above description that I have provided a simple, inexpensive and efficient electrolytic water correction device particularly adapted for use in boilers having low water levels and that the device permits of ready assembly and replacement of the component parts thereof. Furthermore, no attachment is necessary to the boiler or pipes, and the device is readily and easily removable, without danger of accidental movement out of position.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. An electrolytic water correction device especially adapted for positioning between adjacent pipes of a low water level boiler, comprising a cylindrical core of negative metal of the electromotive force series, a helical coil of positive metal of the electromotive force series fitted snugly around said core and having its ends bent inwardly across the ends of said core to secure the core therein, a pair of triangular support members of positive metal of the electromotive force series positioned on said core having central openings larger than the core but smaller than the outside diameter of said coil, said support members having recesses extending outwardly from said central openings of such depth as to permit threading of the support members onto the ends of said coil, and opposed fin members of positive metal of the electromotive force series projecting from said support members and longitudinally of the core for increasing the efficiency of the device, said support members being adapted to be positioned between adjacent pipes of a boiler with said fins insuring against the device falling between the pipes when the core is expended.

2. An electrolytic water correction device especially adapted for positioning between adjacent pipes of a low water level boiler comprising a cylindrical core of negative metal of the electromotive force series, a helical coil of positive metal of the electromotive force series wrapped around said core and having its ends bent inwardly across said core ends to secure the core therein, a pair of triangular support members of positive metal

of the electromotive force series mounted on said core having central openings larger than the core but smaller than the outside diameter of said coil, said support members having recesses extending outwardly from said central openings of a depth permitting threading of the support members onto the ends of said coil, said support members being adapted to be wedgingly positioned between adjacent pipes of a boiler for ready mounting of said device in a low water level boiler.

3. An electrolytic water correction device comprising a core of negative metal of the electromotive force series, a helical coil of positive metal of the electromotive force series partially enclosing said core, a pair of triangular support members mounted on said core in a plane lying at right angles to the core axis having wedge shaped portions for mounting the device between adjacent pipes of a boiler or the like and having openings for threading of said support members onto said coil, and fin members of positive metal of the electromotive force series projecting from said support members and extending axially of said core for increasing the efficiency of the device and insuring the device will not become dislodged from said pipes as the core is expended.

4. An electrolytic water correction device especially adapted for positioning between adjacent pipes of a low water level boiler comprising a cylindrical core of negative metal of the electromotive force series, a helical coil of positive metal of the electromotive force series surrounding said core, a pair of triangular support members mounted on said core having central openings larger than the core but smaller than the outside diameter of said coil, said support members having recesses extending outwardly from said central opening for threading of the support members onto the ends of said coil, and opposed fin members projecting from said support members longitudinally of the core, said support members being adapted to be wedgingly positioned between adjacent pipes of a boiler with said fins insuring against the device falling between the pipes when the core is expended.

5. An electrolytic water correction device especially adapted for mounting on adjacent pipes of a low water level boiler comprising a cylindrical core of a negative element of the electromotive force series, a helical coil of positive metal of the electromotive force series surrounding said core, and a support member mounted on said core adjacent each end thereof, said members having central openings larger than the core but smaller than the outside diameter of said coil and recesses extending outwardly from said central opening for threading of the support members onto the ends of said coil, said support members having a pair of convergent sides forming a wedge portion which may serve to support said device between a pair of adjacent pipes, said wedge portion extending radially outward from said core and lying in a plane at approximately a right angle to the core axis.
